Primary Examiner — Darlington Ly(74) *Attorney, Agent, or Firm* — Birch, Stewart, Kolasch & Birch, LLP(57) **CLAIM**

The ornamental design for tire, as shown and described.

DESCRIPTION

1. Tire

1.1 is a front elevation view of a tire showing my new design;

1.2 is a rear elevation view thereof;

1.3 is a right side elevation view thereof, of which the left side elevation view is a mirror image;

1.4 is a top plan view thereof, of which the bottom plan view is a mirror image;

1.5 is a front perspective view thereof;

1.6 is an enlarged front elevation view of portion 6-6 in reproduction 1.1;

1.7 is an enlarged partial perspective view of portion 7-7 in reproduction 1.5;

1.8 is an enlarged partial perspective view of the portion 8-8 in reproduction 1.5;

1.9 is an enlarged cross-sectional partial view thereof taken in the direction of line 9-9 of reproduction 1.1;

1.10 is an enlarged front elevational view of portion 6-6 in reproduction 1.1; and

1.11 is a cross-sectional view of the radial member taken along the line 11-11 in reproduction 1.10.

The broken lines in the reproductions illustrate portions of the tire that form no part of the claimed design.
